T. H. FOLLIOTT.
DOOR SPRING.
APPLICATION FILED MAR. 14, 1921.

1,413,717.

Patented Apr. 25, 1922.

UNITED STATES PATENT OFFICE.

THOMAS HENRY FOLLIOTT, OF WINNIPEG, MANITOBA, CANADA.

DOOR SPRING.

1,413,717.

Specification of Letters Patent. Patented Apr. 25, 1922.

Application filed March 14, 1921. Serial No. 452,021.

To all whom it may concern:

Be it known that I, THOMAS HENRY FOLLIOTT, a subject of the King of Great Britain, of the city of Winnipeg, in the Province 5 of Manitoba, Canada, have invented certain new and useful Improvements in Door Springs, of which the following is the specification.

The invention relates to improvements in 10 door springs and an object of the invention is to provide a door spring which can be set to hold the door either closed or open as occasion requires.

A further object is to construct the appliance in a simple, durable and inexpensive manner and so that it can be readily attached to existing doors and frames and can be relied upon at all times to do the work for which it is designed.

20 A further object is to arrange the appliance so that the various springs employed can be adjusted to suit conditions.

With the above more important objects in view the invention consists essentially in the 25 arrangement and construction of parts hereinafter more particularly described and later pointed out in the appended claims, reference being had to the accompanying drawing in which:—

30 Fig. 1 is a side view of the appliance as it appears in use and set to normally hold the door closed.

Fig. 2 is a plan view of the parts as they appear in Fig. 1.

35 Fig. 3 is a side view of the appliance as it appears on the door and set to hold the door open.

Fig. 4 is a plan view of the parts as they appear in Fig. 3.

40 Fig. 5 is an enlarged detailed vertical sectional view through the main spring of the appliance.

Fig. 6 is an enlarged detailed horizontal sectional view at 6—6' Fig. 3, and looking 45 downwardly.

Fig. 7 is an enlarged detailed sectional view through the guide rod and showing the roller.

50 In the drawing like characters of reference indicate corresponding parts in the several figures.

According to present practice doors such as screen doors are held normally closed by the action of a spring applied usually at the hinge side of the door and operating to hold 55 the door normally closed. It is sometimes desirable however to have the door remain open and in the majority of cases such is done by blocking the door with a weight or providing a special hook and catch where- 60 by the door can be positively held open against the action of the spring.

According to my invention however I construct my spring so that it can be used for the double purpose, either that of holding 65 the door closed or of holding it open, which is an important advantage.

Referring now to the drawing:—

1 represents the customary door frame and 2 the door mounted in the frame and carried by the usual hinges, one of which is indicated at 3. 4 is the jamb strip against which the door closes. In the present instance the door is shown as a screen door and presents centrally disposed cross strips 5 75 and 6. 7 is a fastening plate securely fastened as by wood screws indicated at 8 to the door frame on the hinge side and aligned with the strip 5. The fastening plate is formed with an outwardly directed extension 9 which carries a pivot bolt 10. On the bolt 10 I mount pivotally a bracket 11 having the ends 12 and 13 thereof bent in the same direction and at right angles to the body part and providing bearing arms for a comparatively 85 long bolt 14 fitted at one end with a head 15 and at the other with a wing nut 16. Here it will be observed that the pivot bolt 10 is immediately adjoining the end 12 of the bracket. On the bolt 14 and between the 90 arms I mount rotatably a sleeve 17 which is formed integral with an arm 18 extending towards the door in advance of the strip 5. The free end of the arm is bent to provide a loop 19 and carries a roller 20 within the 95 loop. 21 is a toothed wheel mounted on the bolt 14 adjacent the arm 18 and 22 is a locking plate mounted on the bolt and provided with a tongue 23 passing through a slot 24 in the arm and entering one or other of the 100 openings between the teeth of the wheel.

This locking plate is held in place by the

wing nut. On the sleeve I mount a coiled spring 25 having one end hooked around the arm 18 and the other end entered into one or other of the openings between the teeth 5 of the wheel 21. The latter end of the spring is shown best at 26 Fig. 6. By this arrangement it is possible for one to increase or decrease the tension of the spring as he can first set the toothed wheel as he 10 wishes and then lock the tongue to hold the toothed wheel locked in that set position.

This adjustable spring locking arrangement is now in use and is not of itself new, being simply herein shown as a means for 15 adjusting the tension of the spring.

With the bracket set in what might be termed the up position or as shown in Fig. 1 the spring is acting to forcibly throw the arm 18 towards the door and to resist outward pull. The roller 20 rides a shaft or rod 27 carried by and spaced from the bar 5 and running lengthwise thereof. 28 and 29 are cushioning springs mounted on the rod and 30 is a collar slidably mounted on 25 the rod and provided with a jamb screw 31 whereby it can be fixed in any adjusted position.

According to the above arrangement and with the parts set as in Figures 1 and 2 of 30 the drawings, it will be obvious that the spring 25 acts to press the arm 18 towards the door and the arm acting through the roller and rod holds the door closed.

When the door is opened by one passing 35 through the arm swings outwardly against the action of the spring 25 and the roller rides in and out on the rod. One can adjust the spring 29 by setting the sleeve 30 so that the said spring will act against the 40 spring 25 and cushion the door against slamming when it is approaching closed position.

If one desires to have the door remain open all that he requires to do is to swing the bracket downwardly from the position it 45 has in Fig. 1 to the position it occupies in Fig. 3. In doing this one reverses the action of the spring 25 as in shifting the bracket the arm is swung around to the inner side 50 of the rod and acts under the action of the spring 25 to swing the door open and hold it so. The spring 28 acts as a cushion for the door when it is approaching the open position.

I might here explain that in Figures 3 and 55 4 of the drawings I have shown the door as closed. This is not a correct position as, as shown, the spring 25 would cause the opening of the door. However, one can consider the door held against opening in so far as 60 these views are concerned.

What I claim as my invention is:—

1. The combination with a hinged door and door frame, of a reversible bracket pivotally attached to the door frame, a spring 6 actuated pressure arm carried by the bracket

and having the extending end anchored to the door but movable in respect to the same, said bracket arm and anchoring means being desired in one position of the bracket to effect an inward pressure of the arm towards the door under the action of the spring and an outward pressure of the arm on the door in the reverse position of the bracket. 70

2. The combination with a hinged door 75 and door frame, of a bracket pivotally attached to the door frame and vertically swingable, a spring pressed pressure arm carried by the bracket and extending to the outer side of the door, means connecting the extending end of the arm to the door whilst allowing of end and rotary movement of the arm in respect to the door, said arm being designed in one position of the bracket to effect an inward pressure on the door and in the other position of the bracket an outward pressure on the door. 80

3. The combination with a hinged door and door frame, of a horizontally disposed guide rod secured to and spaced from the door, an arm extending from the frame to the guide rod and having the end attached to the guide rod, the attachment permitting of a relative end and rotary movement of the arm in respect to the rod and reversible 90 spring pressure means carried by the door frame and operating on the arm. 95

4. The combination with a hinged door and door frame, of a bracket pivotally attached to the door frame and vertically 100 swingable, a spring actuated pivoted pressure arm carried by the bracket and extending in advance of the door, a horizontally disposed guide rod spaced from and secured to the door, means connecting the pressure arm to the guide rod, said means permitting of the rotary and endwise movement of the pressure arm in respect to the guide rod, said pressure arm in one position of the bracket being outside the guide rod and in the other position of the bracket between the guide rod and the door. 105

5. The combination with a hinged door and door frame, of a bracket pivotally attached to the door frame and vertically 115 swingable, a rotatably mounted sleeve carried by the bracket, a pressure arm extending from the sleeve towards the door, a pressure spring mounted on the sleeve and engaging the pressure arm and the bracket, a horizontally disposed guide rod secured to and spaced from the door and means connecting the extending end of the pressure arm to the guide rod, said means permitting of an endwise and rotary movement of the 120 pressure arm in respect to the guide rod. 125

6. The combination with a hinged door and door frame, of a bracket pivotally attached to the door frame and vertically swingable, a rotatably mounted sleeve car- 130

ried by the bracket, a pressure arm extending from the sleeve towards the door, an adjustable pressure spring mounted on the sleeve and engaging the pressure arm and the bracket, a horizontally disposed guide rod secured to and spaced from the door, a loop formed at the free end of the pressure arm and passing around the guide rod, a roller associated with the loop and riding the

guide rod and cushioning springs mounted 10 on the opposite ends of the guide rod.

Signed at Winnipeg, this 16th day of February, 1921.

THOMAS HENRY FOLLIOTT.

In the presence of—

GERALD S. ROXBURGH,
K. B. WAKEFIELD.
